Patented Apr. 11, 1916.

William I. Davis, ^{Inventor}
By Lancaster and Allume _{his Attorneys}

UNITED STATES PATENT OFFICE.

WILLIAM I. DAVIS, OF LITTLE ROCK, ARKANSAS.

DESIGN FOR A CAMPAIGN-BUTTON.

48,856.

Specification for Design.

Patented Apr. 11, 1916.

Application filed March 4, 1916. Serial No. 82,254. Term of patent 3½ years.

To all whom it may concern:

Be it known that I, WILLIAM I. DAVIS, a citizen of the United States, residing at Little Rock, in the county of Pulaski and State of Arkansas, have invented a new, original, and ornamental Design for Campaign-Buttons, of which the following is a specification, reference being had to the accompanying drawing, forming a part thereof.

The figure is a plan view of a campaign button, showing my new design.

I claim:

The ornamental design for a campaign button, as shown.

WILLIAM I. DAVIS.
